UNITED STATES PATENT OFFICE

160,598

BABY STROLLER

Robert C. Heideman, Los Angeles, Calif., assignor to American Carry-Products Company, Inc.,
Burbank, Calif., a corporation of California

Application April 18, 1947, Serial No. 138,480

Term of patent 14 years

(Cl. D14—14)

To all whom it may concern:

Be it known that I, Robert C. Heideman, a citizen of the United States, residing at Los Angeles, in the county of Los Angeles and State of California, have invented a new, original, and ornamental Design for a Baby Stroller, of which the following is a specification, reference being had to the accompanying drawing, forming a part thereof.

Figure 4 is a view showing said device in a folded position taken from the rear thereof.

I claim:

The ornamental design for a baby stroller, substantially as shown.

ROBERT C. HEIDEMAN.
